UNITED STATES PATENT OFFICE.

WILLIAM EDWARD BRYAN, OF KEGWORTH, DERBY, ENGLAND, ASSIGNOR TO SLACK & PARR LIMITED, OF KEGWORTH, DERBY, ENGLAND.

PETROL AND OTHER MEASURED-QUANTITY DELIVERY PUMP.

Application filed March 25, 1927, Serial No. 178,379, and in Great Britain November 3, 1926.

This invention relates to coin-free apparatus for controlling the operation of petrol and other measured quantity delivery pumps of the type in which the coin-free mechanism is located adjacent to an externally moving part on the delivery pump, in such a manner as to lock the delivery pump and prevent its operation except when a coin has been inserted of the predetermined value 10 when a predetermined quantity of petrol or other liquid may be delivered in exchange for the coin inserted.

The apparatus in accordance with this invention is preferably constructed in such a 15 way as to be applicable to measured quantity delivery pumps already in existence, and consists of means for controlling the rack which is usually used for operating the piston rod controlling the delivery of the 20 petrol or other liquid.

To enable this rack to be operated through a complete stroke on the insertion of a coin into the coin-free apparatus, an auxiliary lever is employed which utilizes the coin 25 as an intermediate key between a sliding part or plunger operated by the auxiliary lever and a slide which operates ratchet pawls for controlling the direction of movement of the rack. The ratchet pawls are 30 so arranged that the rack may only be moved in one direction at one time and having commenced a movement in one direction the coin-free apparatus ensures the continued movement in that direction until the 35 rack has moved to the predetermined length of stroke.

The rack having completed its stroke, is then permitted by the pawls, which reverse their restrictive control, to return to the 40 initial position from which the rack originally started. The pawls therefore have teeth oppositely placed, which engage oppositely directed teeth on the rack or oppositely directed teeth on a rotary part which 45 gears with the rack attached to the piston rod.

A lost motion connection is interposed between the rack and the piston rod of the pump, or between the rotary part which is 50 controlled by the pawls and the connection through intermediate gearing with the rack attached to the piston rod.

The coin is received in a receptacle in

the coin-free apparatus and slides through a channel on to two side stops which permit 55 a coin which is too small to pass, but which arrest and hold in position a coin of the correct size. A coin larger than the correct size can not be inserted in the slide. The correct sized coin having been held by 60 the side stops, is located opposite the end of the slide which is formed with a knife-edged projection.

A plunger opposite to the knife-edged projection has two forwardly projecting 65 parts which, when the plunger is pressed forward by the auxiliary lever, bear against the sides of the coin, imparting pressure to the slide through the knife-edged projection which is met centrally in the coin, with the 70 result that the power for moving the slide which is imparted by the auxiliary lever through the plunger tends to bend the coin, and the strength of the coin is therefore tested. Bad coins and ordinary metal discs 75 become bent during this test, and by bending fall into the receptacle without permitting the auxiliary lever to transmit the necessary motion to the slide. Washers with 80 central holes also fail to complete the necessary connection between the plunger and the slide.

If the coin inserted is of the correct size and strength, the forward movement of the auxiliary lever causes the slide to advance. 85 This movement of the slide removes one pawl from its notch, restraining the commencement of the measuring stroke of the piston rod and inserts the other pawl into its notch which allows the rack to be moved only in 90 the measuring direction.

When the slide has been moved to its full distance, an additional pawl enters a notch in the slide and holds the slide in the position which permits the rack to be carried 95 through a complete stroke, and when the rack has completed its stroke, a stop on the rack, or a part moved in unison with the rack, engages the additional pawl and lifts it out of the notch in the slide, which is 100 then returned to its initial position by a spring thus reversing the restrictive control of the pawls and permitting the rack to be moved in the opposite direction back to the ordinary or initial position ready for a further 105 operation of the piston. Although a

- slide, returnable by elastic means, has been described and has been illustrated in the drawings for carrying or operating the release mechanisms, it is obvious that a rocking or pivoted part could be employed for this purpose in the place of a horizontal slide. For convenience however, the term slide used in the specification includes all rocking or pivoted parts.
- 10 Two examples of apparatus of coin-freeed mechanism are illustrated in the accompanying drawings, Figs. 1 to 11 relating to a coin-freeed apparatus which is applied directly to the rack of a pump above the ordinary operating handle and Figs. 12, 13 and 14 show the coin-freeed apparatus applied to a rotary member carried on the pump operating spindle. The types of pumps are somewhat different but it will be readily understood that the coin-freeed apparatus can maintain the distinctive features and be still open to modified design to suit pumps of other various types.
- 15 20 Referring to the drawings, Fig. 1 is a vertical section, and Fig. 2 a plan view of the coin-freeed mechanism, Fig. 9 is a vertical section showing the mechanism in operative position, Fig. 10 is a similar view showing the coin-freeed mechanism thrown out of operation, and Fig. 11 is a plan view of the same parts.

25 Figs. 12 and 13 are respectively a sectional elevation and plan view of the coin-freeed apparatus applied to a pump of different construction, and Fig. 14 is a detail view.

30 Referring more particularly to Figs. 1 to 11 the coin-freeed mechanism is contained within a casing A, one wall of which is formed with an aperture A¹ to receive the coin which passes down a chute A² until arrested by side stops A³ opposite a tubular boss A⁴. Within the casing A is a vertically extending rack B which is connected at its lower end with the pump piston rod B¹ through a lost motion device which permits the rack to move up or down a short distance before moving the pump piston rod. The provision of means for allowing a lost motion between the rack and the pump piston rod prevents the movement of the pump piston rod by a slight reciprocating movement of the operation of handle J. The rod B¹ is shown in this example as having an enlargement B² on its upper end enclosed within a cylindrical extension B³ of the rack B having an inturned flange at its base.

35 40 Pivoted within the casing A at opposite sides of the rack B are two pawls C, C¹ adapted to engage with oppositely directed ratchet teeth formed in the sides of the rack, and movable horizontally in guides within the casing is a slide D formed with a notch D¹ in its underside and having at one end a knife-edged projection D², its

other end is formed into a spindle entering a sleeve A⁵ formed in the casing. The two pawls are drawn towards each other by a spring connection attached to pins C² and C³ projecting from the pawls C, C¹.

45 50 Within the tubular boss A⁴ is slidably mounted a plunger E; its inner end opposite to the knife-edged projection D² is so shaped as to form two points which will bear against the sides of the coins when the plunger E is pressed inwardly by the auxiliary lever F (see Fig. 4). The lever F is pivoted to a lug carried by the tubular boss A⁴.

55 60 Pivottally mounted above the slide D is an arm G having on its rear side a thickened portion G¹, see Fig. 5. This arm acts as a catch plate, one edge of the thickened portion G¹ forming a tooth to engage with notches in the upper side of the slide D, and the arm is formed at one end with a recess G² suitably shaped to engage with the pin C² of the pawl C, when the arm G is swung upon its pivot, while the end G³ is shaped to act with a cam action upon a pin projecting from a sliding member H, one end of which sliding member enters a recess B⁴ formed in one side of the rack B, while the other end of the sliding member passes through a hole in the casing into the coin aperture A¹.

65 70 Upon the face of the rack B is formed a slot B⁵ within which is adjustably mounted a projecting stop B⁶, which upon the rack arriving at its predetermined height, will engage with the under side of the arm G¹ and lift it out of the notch in the upper side of the slide D.

75 80 Upon the insertion of a coin into the aperture A¹ it passes down the shute A² and is arrested by a side stop A³ within the casing. The lever F is then pressed inwardly, causing the two points on the inner end of the plunger E to bear upon the coin and press it against the knife-edged projection D² (see Fig. 4). Further pressure by the lever F causes the slide D to be traversed, the leading edge of the slide engaging the pin C² upon the pawl C lifting it out of its notch upon one side of the rack B, while the spring connection to the pin C² causes the pawl C¹ to be drawn into engagement with the teeth on the opposite side of the rack B. When this action has been effected the edge G¹ upon the arm G falls into the notch D¹ and locks the slide from backward movement. This position of the mechanism is shown at Fig. 9.

85 90 The rack B and pump piston rod B¹ are now free to be moved upwardly to supply the liquid. The operator will then, by rotation of the handle J and gear J¹, (Figs. 7 and 8) which engages with teeth on the rack B, commence to raise the rack, but before doing so, as will be seen from Figs. 7 and 8,

it is necessary to release the lever F to allow the handle J to pass freely in its rotation. The lever F is so arranged that when pressed inwardly it will intercept and prevent the 5 rotation of the pump operating handle J. Upon the release of the lever F the plunger E is brought back to its outward position by means of a spring, and the coin is released and falls into a receptacle within the 10 casing A.

Upon the first upward movement of the rack the sliding member H will be pushed out of the recess B⁴ and will enter the coin aperture A¹, and thus prevent any further 15 coins being placed therein.

It will be seen that the rack can only move in an upward direction and upon the completion of its stroke the stop B⁶ will engage the under side of the thickened portion G¹ 20 of the arm G and lift it out of the notch D⁸, thereby freeing the slide D which, by means of a spring, will be returned to its initial position, and at the same time will engage the pin C³ and lift the pawl C¹ out of engagement with the rack, and through the 25 spring connection, will draw the pawl C into its notch on the opposite side of the rack.

The rack can then be lowered to its original position ready for the next supply, and 30 until the rack has reached its lowest position, the sliding member H will obstruct the coin slot and prevent the insertion of any coin. On the rack reaching its lowest position, the inner end of the member H will 35 again enter the recess B⁴ in the rack and the coin slot will be open.

The plunger E pressing forward the coin, presses from two sides only and presses the coin against the centrally placed edge D² on the slide D and in order to act as a test for the coins, the slide D is caused to resist movement to a considerable extent, so that the coin interposed must be of a certain strength in order to permit the mechanism 40 to be moved by the force exerted on the coin through plunger E by the lever F. Bad coins and ordinary metal discs are bent in this apparatus and fall into a receptacle, and washers do not complete the connection between the plunger and the sharpened edge.

At Fig. 6 a means is shown for giving the necessary resistance to movement of the slide D and for preventing undue strain being produced upon the return of the slide. 45 The rear of the slide is recessed at D⁴, into which a spring-pressed ball D⁶ enters and the first movement of the slide D has to overcome the spring pressure of this ball before compressing the return spring D⁸.

When it is desired to disconnect the coin freed mechanism and use the pump in the ordinary manner, the operator takes hold of the arm G and draws it forward, compressing the spring G⁴ which surrounds the pivot 50 of the arm, as will be seen at Fig. 11. The

arm G is then rocked upon its pivot until its recess G² engages the pin C² and removes the pawl C from its notch while the opposite end G³ at the same time engages a pin on the sliding member H, and causes it to enter 70 the coin aperture A¹ and prevent the insertion of coins. The mechanism in this position is shown at Figs. 10 and 11, and it will be seen that both pawls are held disengaged from the rack which can be raised or lowered at will. 75

To prevent the operator, after the insertion of the coin, pressing the lever F a short distance and withdrawing, an additional notch D⁷ is formed in the upper edge of the 80 slide D, into which the edge of the part G¹ will enter during the traverse of the slide and prevent backward movement of the slide.

Referring now to Figs. 12 to 14 the pawls 85 C and C¹, pivoted to the casing A, are arranged to engage a ratchet wheel K fixed on the pump operating spindle K¹, the pins C² and C³ of the pawls C C¹ are connected, as before described and pass through notches 90 formed in the under side of the slide D. The spindle K¹ carries, mounted loosely thereon a pinion L, upon one face of which are outstanding dogs L¹ which upon rotation of the pump spindle engage with similar dogs L² carried by the spindle K¹ which enter loosely between the dogs L¹, permitting a certain distance of lost motion between the spindle K¹ and the movement of the pinion L. The pinion L gears through 100 wheel L³ and pinion L⁴, with a pump operating rack M.

Fixed to the spindle K¹ is a pinion N gearing with a wheel N¹, the face of which carries a cam surface N² and an adjustable finger N³. Upon the rotation of the operating handle on the spindle K¹, the wheel N¹ will rotate and the cam surface N² will rock a lever O which is pivoted at its lower end to the casing A, thereby sliding a member H 110 into the coin aperture A¹ and preventing further coins being placed therein. 105

When the spindle K¹ has been rotated to the predetermined extent, the finger N³ will engage the under side of an extension G⁵ of the rocking arm G and will lift the edge G¹ out of the notch D⁸ in the slide D, into which the edge G¹ had entered to lock the slide in its forward position when operated by a coin, as before described. 115

In adapting the coin-free mechanism to a pump of this construction, the lever F does not obstruct the operating handle J of the pump as described in the previous example and to ensure that it shall be compulsory for the lever F to assume its outward position before the actuation of the pump, a rod P, sliding in bearings in the casing, bears with its inner end against the lever O, whereby when the cam N² acts to rock the lever O, 125 130

the rod P will be pressed outwardly against the under side of the lever F to prevent its being held in its forward position.

When it is desired to disconnect the coin-freeed mechanism and use the pump freely, the pawl C¹ is rocked out of engagement with the ratchet K by means of an arm C⁴ pivotally mounted on the pin C³ of the pawl C¹, at the same time passing the shoulder C⁵ on the outer end of the arm C⁴ into engagement with a pin H¹ on the sliding member H, whereby the said member is projected into the coin aperture A¹ and prevents further admission of coins while holding the pawl C¹ out of engagement. The pump operating spindle K¹ can then be freely rotated in either direction.

What I claim as my invention and desire to secure by Letters Patent is:—

20 1. Apparatus for controlling the operation of petrol and other measuring quantity delivery pumps, comprising a casing attached to the pump frame, bearings in the casing suitable for carrying a slide, a slide 25 carried on such bearings, coin freed means for traversing such slide, two oppositely directed pawls fulcrumed in the casing, abutments on the slide located so as to engage the said pawls, a rack having oppositely directed teeth located between the pawls, lost motion means connecting the rack to the pump permitting the said pump to operate only after the lost motion is taken up, means on the slide for rocking both pawls to engage one pawl or the other pawl with the rack when the slide is traversed, means to return the slide to its initial position when released, means on the slide to hold it at the end of its traverse, means on the rack to release the slide when the said rack has arrived at the end of its stroke, thereby reversing the pawls and permitting the rack to return to its initial position and the pump to be ready to commence a new measuring 40 operation.

2. Apparatus for controlling the operation of petrol and other measured quantity delivery pumps, comprising a casing attached to the pump frame, bearings in the casing suitable for carrying a slide, a slide carried on such bearings, coin freed means for traversing such slide, two oppositely directed spring actuated pawls fulcrumed in the casing, abutments on the slide located so as to withdraw one or other of the said pawls against the direction of its spring pressure, a rack having oppositely directed teeth located between the pawls, means to return the slide to its initial position when released, a trigger adapted to hold the slide at the end of its traverse, an adjustable abutment on the rack adapted to release the slide when the said rack has arrived at the end of its stroke, thereby reversing the pawls and permitting the rack to return to its initial

position and the pump to be ready to commence a new measuring operation.

3. Apparatus for controlling the operation of petrol and other measured quantity delivery pumps, comprising a casing attached to the pump frame, bearings in the casing suitable for carrying a slide, a slide carried on such bearings, a thrusting member operable from the exterior of the casing and opposite the slide, coacting parts on the slide and on the thrusting member adapted to connect with each other on the insertion of a coin between them, two oppositely directed spring actuated pawls fulcrumed in the casing, abutments on the slide located so as to withdraw one or other of the said pawls against the direction of its spring pressure, a rack having oppositely directed teeth located between the pawls, means to return the slide to its initial position when released, a trigger adapted to hold the slide at the end of its traverse, an adjustable abutment on the rack adapted to engage said trigger to release said slide when the said rack has arrived at the end of its stroke, thereby reversing the pawls and permitting the rack to return to its initial position and the pump to be ready to commence a new measuring operation.

4. Apparatus for controlling the operation of petrol and other measured quantity delivery pumps, comprising a casing attached to the pump frame, bearings in the casing adapted to carry a slide, a slide carried on such bearings, a spring pressing between a seat on the casing and the slide tending to press the slide to its initial position, a hand-operated means outside the casing connected with a thrusting device passing through and entering the casing opposite the end of the slide, engaging parts on the slide and on the thrusting device adapted to receive a coin between them, a rack having two sets of teeth oppositely directed said rack being connected to the piston rod of the delivery pump, two pawls oppositely directed for engaging one at a time with the teeth of the rack opposite to which they are located, means on the slide to actuate the pawls to release one and engage the other of said pawls to and from the rack when the slide is traversed, means for holding the slide at the end of its traverse, means for releasing the slide on the completion of the measuring stroke of the piston of the pump and to permit the said piston to be returned to its initial position.

5. Apparatus for controlling the operation of petrol and other measured quantity delivery pumps, comprising a casing attached to the pump frame, bearings in the casing adapted to carry a slide, a slide carried on such bearings, a spring pressing between a seat on the casing and the slide tending to press the slide to its initial position, a

- hand-operated means outside the casing connected with a thrusting device passing through and entering the casing opposite the end of the slide, an engaging part on the 5 slide located centrally opposite the thrusting device, two engaging parts on the thrusting device adapted to engage opposite sides of a coin when such coin is supported with its centre opposite the engaging part on the 10 slide, a rack having two sets of teeth oppositely directed, two pawls oppositely directed for engaging one at a time with the teeth of the rack opposite to which they are located, means on the slide to actuate the 15 pawls to release one and engage the other of the said pawls to and from the rack when the slide is traversed, means for holding the slide at the end of its traverse, means loosely connecting the rack with the piston rod of 20 the delivery pump, means for releasing the slide on the completion of the measuring stroke of the piston of the pump whereby the said piston is permitted to be returned to its initial position.
6. Apparatus for controlling the operation of petrol and other measured quantity delivery pumps, comprising a casing attached to the pump frame, bearings in the casing adapted to carry a slide, a slide carried on such bearings, a spring pressing between a seat on the casing and the slide tending to press the slide to its initial position, a hand-operated means outside the casing connected with a thrusting device passing 25 through and entering the casing opposite the end of the slide, engaging parts on the slide and on the thrusting device adapted to receive a coin between them, stops on the casing adapted to support the coin before 30 it is gripped between the thrusting device and the slide, a rack having two sets of teeth oppositely directed said rack being connected to the piston rod of the delivery pump, two pawls oppositely directed for engaging one at a time with the teeth of the rack opposite 35 to which they are located, means on the slide to actuate the pawls to release one and engage the other of said pawls to and from the rack when the slide is traversed, means for holding the slide at the end of its traverse, 40 means for releasing the slide on the completion of the measuring stroke of the piston of the pump and to permit the said piston to be returned to its initial position.
- 45

means on the slide to actuate the pawls to release one and engage the other of said pawls to and from the rack when the slide is traversed, means for holding the 50 slide at the end of its traverse, means for releasing the slide on the completion of the measuring stroke of the piston of the pump and to permit the said piston to be returned to its initial position. 55

7. Apparatus for controlling the operation of petrol and other measured quantity delivery pumps, comprising a casing attached to the pump frame, bearings in the casing adapted to carry a slide, a slide carried on such bearings, a spring pressing between a seat on the casing and the slide tending to press the slide to its initial position, a hand-operated means outside the casing connected with a thrusting device passing 60 through and entering the casing opposite the end of the slide, engaging parts on the slide and on the thrusting device adapted to receive a coin between them, stops on the casing adapted to support the coin 65 before it is gripped between the thrusting device and the slide, a coin intercepting member adapted to obstruct the entrance for the coin after the piston of the pump has left its initial position, a rack having two sets of teeth oppositely directed said rack being connected to the piston rod of the delivery pump, two pawls oppositely directed for engaging one at a time with the teeth of the rack opposite 70 to which they are located, means on the slide to actuate the pawls to release one and engage the other of said pawls to and from the rack when the slide is traversed, means for holding the slide at the end of its traverse, 75 means for releasing the slide on the completion of the measuring stroke of the piston of the pump and to permit the said piston to be returned to its initial position. 80

In witness whereof I have hereunto set my hand.

WILLIAM EDWARD BRYAN.
